214,501

VENT COVER OR SIMILAR ARTICLE

Roland G. Eklund, Kansas City, Mo., assignor to Borg-Warner Corporation, Chicago, Ill., a corporation of Delaware

Filed May 13, 1968, Ser. No. 11,905

Term of patent 14 years

Int. Cl. D23—04

U.S. Cl. D23—151

I claim:

The ornamental design for a vent cover or similar article, substantially as shown.
